UNITED STATES PATENT OFFICE.

ERICK P. BERGMAN, OF CONCORDIA, KANSAS.

WINDMILL.

No. 849,192.

Specification of Letters Patent.

Patented April 2, 1907.

Application filed April 17, 1906. Serial No. 312,100.

To all whom it may concern:

Be it known that I, ERICK P. BERGMAN, a citizen of the United States of America, residing at Concordia, in the county of Cloud 5 and State of Kansas, have invented certain new and useful Improvements in Windmills, of which the following is a specification.

This invention relates particularly to that type of windmills which are provided with 10 mechanism for converting the rotary motion of the wheel into a reciprocating motion to operate or actuate a pump-rod; and the present invention has for its object to improve the general construction of the support for 15 the wheel, the turn-table, the means for placing the blades of the wheel in different positions, and the connections between the pump-rod and shaft of the wind-wheel, as will be hereinafter set forth, and specifically pointed 20 out in the several claims.

In the accompanying drawings, Figure 1 is a vertical section of a windmill made in accord with my invention, and Fig. 2 is a detail view showing connections between the driven 25 chains and the pump-rod.

Instead of providing the usual built-up tower to support the wheel and its platform such parts are carried by a tubular column A, and to said column there is secured a platform A', guy-ropes a a being secured to the platform, so as to brace the support. The platform has an opening therethrough for the 30 passage of the lower wheel-supporting section F, and above the platform near the upper end of the tubular standard or column there is secured a casting or fixture B, such fixture having a vertical opening therethrough for the passage of the upper section of the head, a flange on such head resting 35 upon ball-bearings seated in a recess, so that they will impinge against the flange and the side of the tubular portion of the head which is passed through the circular opening of the fixture. Below the platform there is secured 40 a casting or fixture C, the opening to one side of the support A being smaller than the opening through the upper fixture B. This lower fixture has a ball-race and an opening for the passage of a bar C', that is also guided by an 45 apertured stud which is secured to the support, the eye through the stud c being on a line with the smaller opening through the fixture C. The vertically-maintained bar C' has fastened thereto an arm e' to engage a 50 slide on the pump-rod C'', the slide being connected to a weighted bell-crank lever for moving another slide to place the blades of the wind-wheel in different positions.

The upper section of the wind-wheel support or its head D has below the flange d a tubular depending part D', that passes through the larger opening of the fixture B, and below the under side of the fixture are bolt-holes for the reception of bolts which connect an intermediate section E to the head. 55

The head D is constructed to provide bearings for the shaft D'', which carries the wheel d' and a slide d'', which is moved upon the shaft D'' by a lever that is pivoted to an arm e, attached to the head, the longer end of the arm carrying a weight, the tendency of the weight being to lower the long end of the lever e' and move the slide forward and turn crank-rods which are connected to the blades of the wheel. The lever e' has attached thereto a flexible connection which passes over a guide-pulley on the upper end of an arm e'', the lower end of the connection being attached to the upper end of a rod C'', the lower end of the rod being fastened to the 60 slide that is engaged by the arm e', and by drawing down on the bar C' the arm e' may be moved to render the wheel idle. It will be noted that the rod C'' passes through the hollow sections of the wheel-support. In 65 line with the shaft D'' is a stub-shaft D', such shaft and the wheel-carrying shaft D'' having fast thereon between the bearings spur-gears that mesh with gears on the ends of a shaft d', so that the shafts will turn in 70 unison, and the adjacent ends of the shafts D'' and D' carry sprocket-wheels d'', about which pass chains d', the chains engaging guide-sprockets D', carried by stub-shafts D', supported by an intermediate section E. The 75 section E at opposite points is enlarged to form bearings for the stub-shafts D', and near the upper and lower ends of the tubular intermediate section or connection are vertical slots m m, through which pass bolts n n, which connect the intermediate section E to the lower portion of the upper section or head D and to the upper part of the lower section F, so that the three sections will be connected to turn in unison, the central section being 80 supported by the chains d' d'. Each chain d' has a link constructed to carry one end of a shaft or cross-bar g, to which is connected a pitman G. The pitman G has therethrough a slot in which is pivoted a cross-head G', the 85

ends of the laterally-projecting upper part of the cross-head engaging recessed guide-bars *h h*, which are carried by the head or upper section D and by the intermediate or suspended section E. The lower ends of the recessed guide-bars *h h* are bolted directly to the intermediate section E, and the upper ends of the bars have therethrough slots for the passage of bolts *h'*. The slots permit vertical movement of the section E, and the pivoted cross-head G' insures a steady movement of the pitman and prevents the chains being twisted or thrown out of alignment with the sprockets over which the chains pass.

- 15 The lower section of the wheel-support is connected to the intermediate section E, and the lower section F has a reduced lower portion that passes through the fixture C, the shoulder *f* resting on the ball-bearings *f'*.
- 20 The pump-rod C' is connected to the pitman G by a suitable coupling that permits the rod to turn in the coupling.

It will be noted that the wheel-support herein shown provides an elongated head which incloses the transmitting mechanism and that the parts are connected to be substantially self-adjusting. The chains are kept taut by the weight of the intermediate section, and the pivoted cross-head overcomes irregularity of movement and jar incident to the change of direction of movement of the pitman in passing the sprockets.

Having thus set forth my invention, what I claim as new, and desire to secure by Letters Patent, is—

- 35 1. In a windmill, the combination of a wind-wheel, its shaft and a stub-shaft, a head having bearings in line with each other for the shaft of the wind-wheel and for the stub-shaft, similar gears and sprockets on the shafts, means for transmitting motion from the shaft of the wind-wheel to the stub-shaft, a pair of chains that engage the sprockets and are driven therefrom, a cross-bar attached to and connecting the chains, a pitman connected between the chains to the cross-bar, the pitman having a cross-head which is pivoted thereto and is adapted to engage with vertical guides attached to the head, substantially as shown.

- 45 2. In a windmill, the combination of a rotary head or support for a wind-wheel, means for driving a pair of chains, a section maintained in vertically-movable engagement with the head, guide-sprockets for the chains the guide-sprockets being carried by the vertically-movable section, a pitman connected to the chains, a cross-head pivoted to the pitman, guides for the cross-head attached to the rotary head or support for the wind-wheel and a lower section connected to

the intermediate section and resting upon a support, substantially as shown.

3. In a windmill, a head having bearings for the shaft of a wind-wheel and a stub-shaft in line with the shaft of the wind-wheel, bearings for the shafts, means for driving the shafts in unison, sprockets on the adjacent ends of the shafts, a section connected to the head so as to turn therewith and to be capable of a vertical movement independent of the head, guide-bars attached to the head and to the section that is connected to such head, shafts carried by the vertically-movable section, sprockets on said shafts, chains that engage the sprockets, a pitman connected to the chains, a cross-head pivoted to the pitman and provided with a member that engages the guide-bars and a pump-rod connected to the pitman, substantially as shown.

4. In combination with a wind-wheel and its support, of motion-transmitting mechanism comprising a pair of driven chains, a pitman connected to both of the chains and to a reciprocating bar, an oscillatory cross-head pivoted to the pitman, guide-bars that are engaged by the head, and a coupling that connects the lower end of the pitman to the reciprocating bar, substantially as shown.

5. In a wind-wheel, a tubular support, a platform attached to the support and provided to one side thereof with an opening, fixtures attached to the support and provided with openings, tubular wheel-supporting sections comprising an upper section or head that is seated on the upper fixture and extends through the opening therein, a lower section that bears upon the lower fixture and extends upward through the platform, and an intermediate connection-section that is coupled to the upper and lower section, substantially as shown.

6. In a wind-wheel, a supporting-column provided with laterally-projecting fixtures and a platform, the fixtures and platform having openings for the passage of turning sections that comprise the head of the wind-wheel, recesses in the upper and lower fixtures adjacent to the openings therethrough, antifriction-bearings in the recesses, horizontal portions attached to the upper and lower sections of the heads for engagement with the bearings and an intermediate section having vertical slots through each end and bolts for connecting such section to the lower end of the upper section and to the upper end of the lower section, substantially as shown.
